ALBERT MURDOCK, OF NORTH BRIDGEWATER, MASSACHUSETTS, ASSIGNOR TO HIMSELF AND HERBERT E. SNOW, OF THE SAME PLACE.

Letters Patent No. 88,895, dated April 13, 1869.

IMPROVEMENT IN SCISSORS.

The Schedule referred to in these Letters Patent and making part of the same.

To all whom it may concern:

Be it known that I, ALBERT MURDOCK, of North Bridgewater, Plymouth county, Massachusetts, have invented a new and improved Spring-Scissors; and I do hereby declare that the following is a full, clear, and exact description thereof, which will enable others skilled in the art to make and use the same, reference being had to the accompanying drawings, forming part of this specification.

Figure 1 represents a side view of my improved spring-scissors.

Figure 2 is an edge view of the same.

Similar letters of reference indicate corresponding parts.

This invention has for its object to construct scissors which can be constantly kept in the hand without being in the way of other work to be done, so that they may be used on sewing-machines, for clipping threads, and other purposes, without requiring the machine to be stopped, and also for other purposes.

The invention consists in arranging on one blade, which is provided with a ring-handle, another blade, without a handle, and held open by a spring.

These scissors can be suspended, by the ring, on the little finger of the right hand, and will not interfere with other work to be done by the same hand, while they can readily be placed with the blades between the thumb and fore-finger, when to be used for clipping thread, cutting cloth, and other purposes.

Heretofore, when, on a machine, scissors had to be used, the machine had to be stopped, in order to enable the operator to take up and use the scissors. Much

time was thus lost. With the aid of my invention, the machine does not have to be stopped at all when the scissors are to be used, and still the scissors will be out of the way when not used.

A, in the drawing, represents one blade of the scissors, provided with a shank or handle, B, on which a ring, *a*, is formed.

C is the other blade, pivoted, by means of a pin, *b*, to the blade A.

D is a spring, fastened with one end to the shank B, while its other end is secured, in suitable manner, to the blade C, as shown, so as to throw it up away from A.

The device is suspended, by the ring *a*, from the little finger of the right hand, and is thus suspended when not used.

When to be used, the edges of the blades are taken between the thumb and fore-finger, without withdrawing the instrument from the little finger, and can then be operated by at intervals forcing the blades together.

I claim as new, and desire to secure by Letters Patent—

As a new article of manufacture, spring-scissors, provided with one shank, having one ring, *a*, and with the spring D, substantially as described, to operate as specified.

The above specification of my invention signed by me, this 5th day of February, 1869.

ALBERT MURDOCK.
